Primary Examiner — Jennifer Rivard*Assistant Examiner* — Melanie Pellegrini(74) Attorney, Agent, or Firm — Reising Ethington P.C.(57) CLAIM

The ornamental design for a ring, as shown and described.

DESCRIPTION

FIG. 1 shows a perspective view of the ring;

FIG. 2 shows a front view of the ring;

FIG. 3 shows a rear side view of the ring;

FIG. 4 shows a left side view of the ring;

FIG. 5 shows a right side view of the ring; and,

FIG. 6 shows a top view of the ring, the bottom view being identical to the top view.

The broken lines shown in the drawings illustrate portions of the ring and form no part of the claimed design.
